UNITED STATES PATENT OFFICE

ERNEST DUNFORD, OF ST. LOUIS, MISSOURI, ASSIGNOR TO LANDIS MACHINE COMPANY, OF ST. LOUIS, MISSOURI, A CORPORATION OF MISSOURI.

GAUGE FOR SHOE-STAPLER MACHINES OR THE LIKE

Application filed June 7, 1929. Serial No. 369,070.

My invention relates to shoe machinery such as staplers, stitchers, lasters or the like and consists in a novel gauge, for spacing the sole or heel from the fastening parts of the machine.

The main object of my invention is to provide a simple gauge that may be horizontally and vertically adjusted without the necessity of the operator moving from his working position, each adjustment being made by moving a control on the level with the gauge and within easy reach of the operator, standing in working position at the end of the gauge.

Another object of my invention is to provide a gauge that may be readily swung away from the operator when it is not desirable to use said gauge.

In the accompanying drawings which illustrate a selected embodiment of my invention—

Figure 1 is a side view of my invention applied to a stapler showing the throat block of the stapler, and a shoe mounted on the stapler horn with the toe of the shoe over the anvil of said horn and under the throat block.

Figure 2 is a top view of my gauge mechanism.

Figure 3 is a vertical section through my gauge mechanism taken substantially on the line 3—3 of Figure 1.

Figure 4 is a side view of the throat block, heel of the shoe and my gauge vertically adjusted for applying staples to the heel of the shoe.

Fixed to the frame 1 of the stapler device is a bracket 2. A plate or cradle 3 is slidably mounted in a recess in the lower face of said bracket. Plate 3 has depending flanges 4 to which a gauge arm 5 is pivoted by pin 6.

Arm 5 is retained in horizontal position by means of a flat spring 7 secured at one end to one flange 4, a pin 8 passing through the flange with its head projecting outwardly from the flange with spring 7 bearing against the head of pin 8. A hardened insert 9 in arm 5 engages the inner end of pin 8.

Fulcrumed to bracket 2 at 10 is an arm 11 with a handle 12. In the bracket 2 along the arc which the inner end of the arm 11 would describe upon the movement of handle 12 is a

curved slot B. Mounted on arm 11 and adapted to project through slot B is a stud 14. Across plate 3 and substantially perpendicular to the axis of arm 5 is a straight groove A. Journaled on stud 14 and adapted to fit into groove A is a roller 15. At the edge of bracket 2 near handle 12, the bracket is ratcheted at 16. On handle 12 is a spring pawl 17 fitting into ratchet 16.

Thus as the handle 12 is moved to the left, arm 11 swings on fulcrum 10 and the inner end of the arm moves to the right, moving stud 14 in slot B so that roller 15 pushes against the side of groove A and thereby moves the gauge mechanism attached thereto forward toward the throat block 13. Said ratchet and pawl provide a mechanism for graduating said movement and yieldingly holding the gauge mechanism in a given position.

The front of gauge arm 5 has a member 18 which is on approximately the same level as bracket 2. Member 18 mounts a rotatable shank 19 with an enlarged portion 20 at the inner end thereof. Member 18 has an inwardly extending shoulder 21. Between portion 20 and shoulder 21 there is a coiled spring 22. Member 18 has alined notches 23 on its outer face on opposite sides of shank 19. Shank 19 has a diametrical pin 24 normally seated in notches 23 and extending beyond the sides of member 18. Shank 19 mounts on its outer end gauge jaws 25 which hold a gauge block 26 eccentrically of the axis of shank 19. Gauge block 26 is held on shank 19 by means of pin 27.

Gauge block 26 may be positioned above or below the axis of the shank by merely grasping pin 24 and pulling the same forward out of the notches 23 and turning the same, to revolve the shank 19 180° and then allowing the shank to be pulled back by spring 22 to again seat pin 24 in notches 23.

The gauge block is made vertically adjustable because a different vertical position of the block is needed when work is to be done on the heel from that which is required when work is to be done on the sole of the shoe. When working on the sole, the gauge block is put adjacent to the sole itself as this member

is fairly regular in contour and in the finished condition, except as to polishing, and the desired spacing of the staples with reference to the edge of the finished sole may be obtained by so placing the gauge block. But when working on the heel, the gauge block is lowered to a position adjacent to the surface of the body of the heel under the tap, as the tap is irregular in contour and is not cut to the finished shape until after it is stapled on to the heel. By placing the gauge block under the tap and adjacent to the surface of the body of the heel, the desired spacing of the staples with reference to the edge of the finished heel tap may be obtained.

Various changes in the details of construction may be made without departing from the spirit of my invention and I contemplate the exclusive use of such modifications as come within the scope of my claims.

I claim:

1. In a shoe stapling machine or the like, a single gauge block, a member mounting said block and movable to and from a position in which said block may function, and means for adjusting said block horizontally and vertically on said member.

2. In a gauge device for a shoe stapler or like machine, a gauge support arm movable to and from functioning position, a member rotatable on said arm to different functioning positions, a gauge block mounted on said member and held thereby at different functioning levels when said member is rotated to its positions, and means holding said member in its different positions.

3. In a gauge of the class described, a rotatable member, a gauge block immovably mounted on said member eccentrically of the latter's axis of rotation and movable to different functioning positions by rotation of said member, and means yieldingly holding said member and block locked in different functioning positions.

4. In a gauge device for a shoe stapler or like machine, a plate reciprocal towards and from a machine element, a member rotatably mounted on said plate with its axis substantially paralleling the line of reciprocal movement of said plate, a gauge block mounted on said member eccentrically of said axis, means yieldingly holding said plate in desired position and means yieldingly holding said member in desired position on said plate.

5. In a gauge device for a shoe stapler or like machine, a plate, an arm pivoted on said plate to swing from an inoperative position to an operative position, a member rotatable on said arm, a gauge block immovably mounted on said member and movable therewith to different operative positions, and respective yielding elements holding said arm and member locked in selected positions.

6. In a gauge device for a shoe stapler or like machine, a reciprocal plate, an arm

pivoted on said plate to swing from an inoperative position to an operative position, a member rotatable on said arm, a gauge block on said member and movable thereby to different operative positions, and respective yielding elements holding said plate, arm and member in selected positions.

7. In a gauge device for a shoe stapler or like machine, a bracket, a plate slidable in said bracket, a depending flange on said plate, a gauge arm pivoted to said plate, a flat spring, one end of which is secured to the outside of said flange, and a pin extending through the flange and engaging the other end of said spring and a recess in said gauge arm adapted to yieldingly retain said gauge in operative position.

8. In a gauge mechanism for a shoe stapler or like machine, a gauge arm cradle, a gauge arm pivoted to one end of said cradle, a gauge block on said arm, and cooperating means on said cradle and said arm for retaining said arm with said gauge block in operable position, said means being spaced from the pivotal connection of said arm and cradle and on the end of said cradle opposite the end having said pivotal connection, said means being adapted, upon manual pressure on said arm to release said arm, said arm when thus released being adapted to swing on its pivot to move said gauge block into an inoperative position.

9. In a shoe stapler or the like machine, a gauge arm, a shank adapted to revolve on said gauge arm, a spring thrusting said shank inwardly in said arm, a pin extending diametrically of said shank, said gauge arm having notches to receive said pin, and a block eccentrically mounted on the end of said shank, whereby said gauge block may be adjusted vertically by pulling said shank out until said pin is unseated from said notches and making a half turn of the shank and again seating said pin in said notches.

10. In a gauge device for a shoe stapler or the like machine, a machine frame, a bracket secured to said frame, an arm fulcrumed on said bracket, a slot in said bracket, a member extending from one end of said arm and through said slot, said member being adapted to describe an arcuate course in said slot when said arm is moved upon said fulcrum, a plate slidably mounted on said bracket, a gauge arm extending from said plate, a groove in said plate, and a roller on said member extending into said groove, whereby said plate and gauge arm are moved forwards and backwards as said arm is moved on its fulcrum.

11. In combination in a shoe stapler or the like machine, a member for delivering securing means, a shoe support member adjacent thereto, a rotatable bar with its axis of rotation extending towards said members, and a gauge block carried on said bar eccentrically.

5
cally of said axis and at the end of said bar nearest said members and movable with said bar to engage the edge of a shoe sole on said support member at the level of the bottom of said delivery member or to engage the side of a shoe heel on said support member at a point spaced below said level.

10
12. In combination in a shoe stapler or the like machine, a member for delivering securing means, a shoe support member adjacent thereto, an arm pivotally mounted on the machine at one side of said members so as to swing towards the latter and away therefrom, a bar journaled on the outer end of said arm so as to rotate in a direction transversely of the direction of pivotal movement of said arm, and a gauge block eccentrically mounted on the outer end of said bar and movable thereon to engage the edge of a shoe sole on said support member at the level of the bottom of said delivery member or to engage the side of a shoe heel on said support member at a point spaced below said lever or to be swung away from said members by pivotal movement of said arm.
25

In testimony whereof I hereunto affix my signature this 5th day of June, 1929.

ERNEST DUNFORD.
